PORTABLE PLANT PROTECTOR

Hans H. A. Heuer, General Delivery, Miami, Fla.
Filed Sept. 6, 1961, Ser. No. 136,267

1 Claim. (Cl. 50—51)

The present invention relates to a portable cover or roof, and more particularly to such a roof or cover which is particularly or especially suitable for horticultural usage.

An object of the present invention is to provide a portable roof which is adapted to be used for conveniently protecting plants, crops or the like, so that damage to such plants or crops from harsh weather conditions will be eliminated or minimized.

Another object is to provide a portable roof for horticultural uses, wherein the portable roof of the present invention can be readily extended or collapsed as desired or required.

Another object is to provide a device of the character described that may be utilized speedily and with precision by even inexperienced operators.

Further objects and advantages are to provide improved elements and arrangements thereof in a device of the character described that is economical to produce, durable in form, and conducive to the most economical use of materials and uniformity of members formed therefrom.

Still further objects and advantages will become apparent from the subsequent description and specification.

In the drawings:

FIGURE 1 is an end elevational view showing the portable roof of the present invention in use positioned over rows of plants, shrubs, trees or the like.

FIGURE 2 is a fragmentary top plan view, with the parts in the position of FIGURE 1.

FIGURE 3 is a sectional view taken on the line 3—3 of FIGURE 2.

FIGURE 4 is a fragmentary perspective view of the cover.

FIGURE 5 is a sectional view taken on the line 5—5 of FIGURE 2.

FIGURE 6 is a view similar to FIGURE 5 but showing the cover arranged in a partially adjusted or collapsed position.

FIGURE 7 is a fragmentary perspective view illustrating the slots and weighted members in the cover.

FIGURE 8 is a fragmentary elevational view showing the rollers which engage a rail.

FIGURE 9 is a sectional view taken on the line 9—9 of FIGURE 3.

Referring in detail to the drawings, the numeral 30 indicates the roof or structure of the present invention in its entirety, and wherein it will be seen that there is provided a plurality of spaced parallel vertically disposed posts 31, and these posts are arranged in rows, and the lower ends of the posts 31 are suitably mounted or embedded in the ground 32. As shown in the drawings, there is provided horizontally disposed spaced parallel beams or bars 33 which are suitably secured to the upper portions of the posts 31, FIGURE 2, and there is provided a plurality of spaced apart lines or cables 34 which are suitably affixed to the bars 33. The numeral 35 indicates each of the plurality of spaced parallel rails which are connected to the cables 34.

As shown in FIGURE 3, there are provided riders which are indicated generally by the numeral 36, and each of the riders 36 has the same construction and each embodies the body piece 37 which is shaped to include opposed first portions 38 which define axles on which are mounted rollers or wheels 39, and the body piece 37

2

further includes second portions 40 which are arranged at right angles with respect to the first portions 38. There are further provided third portions 41 which are arranged at right angles with respect to the second portions 40, and the numeral 42 indicates fourth portions which are arranged at right angles with respect to the third portions 41, and there is provided a fifth portion 43 which defines a cross member, and the cross member 43 interconnects the fourth portions 42 together.

10 Each rider 36 further includes a draw bar 44 which is shaped to include spaced parallel first sections 45 that are swively connected as at 46 to the first portions 38 of the body piece 37, and the draw bar 44 further includes a cross element 47 which interconnects the first sections 45 together.

15 The numeral 48 indicates the covers which are made of a suitable flexible material, and there is provided on edge portions of the covers 48 eyelets or rings 49 which are pivotally connected to an intermediate portion of a corresponding cross element 47. As shown in FIGURE 7, weighted members or elements 50 are mounted in intermediate portions of the covers 48, and these weighted members 50 are mounted between layers 51 and 52 of the cover 48, so that the cover consists of a double thickness or double layer arrangements as indicated by the numerals 51 and 52.

20 Intermediate portions of the covers are provided with spaced apart slots 53, and there are provided web portions 54 which are interposed between the slots 53, FIGURE 2. The covers are further provided with a plurality of spaced apart cords 55 which are suitably embedded in the cover, the cords 55 can be conveniently embedded between the layers 51 and 52 during the fabrication of the cover. The cords 55 have rings or loops 56 on the outer ends thereof and these rings 56 can be conveniently manually gripped in order to facilitate movement of the cover as desired or required.

25 In FIGURE 1 the numeral 57 indicates plants, bushes, trees or the like growing from the ground 32, and in FIGURE 1 the numeral 58 indicates an individual such as a workman performing various types of horticultural activities beneath the covers in conjunction with the plants 57, and as shown in FIGURE 1 gutters 59 are dug in the ground 32.

30 As shown in FIGURES 1, 3, and 4, when the present invention is being used, the cover hangs downwardly at the intermediate portion thereof due to the provisions of the weighted members 50 and due to the action of gravity, so that with the cover being used the cover has a substantially V-shape in cross section and wherein the lower crease line or body edge portion of the cover is indicated by the numeral 61.

35 As shown in FIGURE 6, the cover 48 can also be moved to a position which causes the formation of fold lines 62.

40 The cords 55 with the loops or rings 56 on the ends thereof provide a means whereby the ring 56 can be manually gripped in order to move the parts to a position such as that shown in FIGURE 6. Also, the ring 56 can be used as an attaching means so that a plurality of the units or covers can be fastened together in the vicinity of the ring 56 so that a structure or roof of any desired length can be made.

45 The slots 53 and apertures 60 permit rain water or the like to drain therethrough and such water is collected in the gutters 59 and the gutters 59 can be constructed so as to cause the drainage to flow off to a desired location or in a desired direction. Also, the provision of the slots 53 in the opening 60 is such that there will be less likelihood of damage to the cover and its associated parts in the event of a storm or the like since the slots and openings will have a tendency to dissipate any vacuum

which might have a tendency to form beneath the cover, but there will be less likelihood of damage to the parts, and this is especially advantageous and in tropical countries or the like where violent storms such as typhoons, monsoons or the like sometimes occur. The cover 48 is made of any suitable material and in addition the cover 48 may be impregnated or coated with a suitable chemical such as a paint and for example aluminum paint may be used to coat the cover 48 in order to help reflect excessive heat from the sun, and the cover 48 is made so that it has a double ply as indicated by the numerals 61 and 62.

It is to be understood that the various parts can be made of any suitable material and the parts can be made in different shapes or sizes as desired or required.

The present invention is especially suitable for horticultural purposes, as for example it may be used in conjunction with trees, bushes, plants or the like as indicated by the numeral 57, and the device may be made large enough so that workman such as the workman 58 can readily walk beneath the cover 48 to cultivate or treat or otherwise gain access to the growing members 57. Or, the device may be made of a relatively small size for use with smaller shrubs, plants, growing vegetables or the like.

The posts 31 are stationary and are arranged so that their lower ends are suitably anchored in the ground 32, and these posts 31 have the beams 33 affixed thereto in any suitable manner, as for example by means of nails or the like, and the lines 34 are suitably affixed to the beams 33, and these lines 34 serve to support the inclined rails 35. As shown in FIGURE 1 a plurality of the covers 48 may be used depending upon the size of the acreage being worked, and one row of posts 31 can function to support a pair of beams 33 as shown in FIGURE 3, whereby adjacent covers 48 can be readily and conveniently supported in the desired and proper manner. The riders 36 serve to operatively connect the outer edge portions of the covers 48 to the rails 35, and the riders 36 include the rollers 39 which are adapted to travel along the rails 35 whereby the parts can be adjusted or moved to their proper location with a minimum amount of friction. Also, the riders 36 are constructed so that accidental separation thereof from the rails will be prevented, and the rollers 39 are spaced from each other and the portions 40 as well as the adjacent elements or portions of the bodypiece 37 are constructed so that there will be clearance between the portions 40 in order to permit the riders 36 to travel or move along the rails 35 without interference from the lines 34. In addition, the draw bar 44 is swivelly connected as at 46 to the body piece 37 so as to permit the swivel action at this point.

The rails 35 are adapted to be made of a suitable material such as scrap iron. There is a gap or space between the rollers 39 which travel along the rails 35 so as to insure that there will be no interference from the lines 34. The cover 48 can be made of a suitable material such as canvas.

Thus, it will be seen that the present invention consists of V-shaped roofs or covers which are pliable, and wherein there are no ribs and wherein the roofs are not fixed to any unyielding framework. The material may be plastic,

paper, fabric or the like. The attached weights 50 or the force of gravity take the place of stiff ribs, and the present invention has an economical construction and an efficient operation as well as a unique and efficient securing means. The inverted riders 36 which carry the weight of the sheets or covers 48, rung on rails or strips 35 by means of two rollers or balls 39. The rails 35 are suspended from the posts 31 which are set in the ground. The sheets or covers 48 have slits or slots 53 for drainage and to allow unrestricted folding. The slots 53 may be in the middle of the sheets or else they may be in the form of openings as indicated by the numeral 69 and such openings can be arranged off to one side on a slope, FIGURE 4. The sheets or covers may be solid for shading and frost and rain protection, or they may be perforated for shading, and such perforations or openings 69 in FIGURE 4 may function for this purpose. The strings or cords 55 may be embedded in the material for strength and convenience in handling. FIGURE 6 illustrates the device in a partially folded position.

Minor changes in shape, size and rearrangement of details coming within the scope of the invention claimed may be resorted to in actual practice, if desired or required.

What is claimed is:

In a plant protector assembly including a pair of horizontally disposed spaced parallel rails supported above a ground surface, a plurality of riders mounted on each rail, each of said riders including a pair of opposed first portions defining axles, second portions each arranged at a right angle with respect to each of said first portions and having one end formed integrally with one end of said first portion, third portions each arranged at a right angle with respect to each of said second portions and having one end formed integrally with one end of said second portion, fourth portions each arranged at a right angle with respect to each of said third portions and having one end formed integrally with one end of said third portion, a fifth portion providing a cross member connecting the other ends of said fourth portions together, and a roller mounted on each axle and rollably engaging the adjacent rail, a U-shaped draw bar having the legs thereof swivelly connected to the parts of said first portions exteriorly of said rollers, and a flexible cover extending between said rails and having the edges thereof secured to the bights of said draw bars, whereby said cover may be drawn along between said rails to shield plants therebetween or withdrawn to a nested and folded position adjacent one or the other adjacent ends of said rails.
